UNITED STATES PATENT OFFICE

BASIL POMEROY COOPER, OF LEICESTER, ENGLAND, ASSIGNOR TO UNITED SHOE MACHINERY CORPORATION, OF PATERSON, NEW JERSEY, A CORPORATION OF NEW JERSEY

APPARATUS FOR NAIL SORTING

Application filed October 11, 1927, Serial No. 225,519, and in Great Britain November 9, 1926.

This invention relates to improvements in apparatus for sorting metallic fastenings and is illustrated herein as embodied in a machine for sorting nails with respect to length.

5 In the manufacture of nails and other metallic fastenings, it sometimes happens that nails of different lengths become mixed either through inadvertence on the part of a workman or, in the manufacture of wire 10 nails, through slippage in the operation of the wire feeding mechanism. Such a mixture of nails of varying lengths is practically unsalable even though each individual nail is perfect. Such mixed nails may be sorted 15 for length by hand picking but this is a slow and tedious, and therefore expensive, operation. Such attempts as have been made to sort metallic fastenings for length by machinery have involved the handling of the 20 different fastenings as individuals and the speed of the operation has accordingly been limited.

It is an object of the present invention to 25 provide an improved apparatus applicable to the sorting of metallic fastenings in bulk without the necessity of first arranging the fastenings in an orderly series. As illustrated herein this sorting is done by presenting a mass of unsorted fastenings to gaging 30 means provided with shallow pockets each of such dimensions that a fastening of greater than the desired length can not be completely received or inserted in a pocket. If an attempt is made to insert a fastening of greater 35 than the desired length in one of the pockets, the fastenings will project therefrom and can be easily and expeditiously removed. Preferably and as illustrated, these pockets are circular and a multitude of them are 40 formed in a receptacle into which a mass of the fastenings may be thrown. The receptacle is agitated and many of the fastenings which are not longer than the limit of toleration enter the pockets. All the fastenings not 45 completely within a pocket are then removed, for example brushed, from the pockets and the remaining fastenings, none of which is over the desired length, are deposited in a suitable receptacle. The sorting is continued 50 in this fashion until substantially all of the

fastenings no longer than the desired length have been removed. The process can be repeated with the longer fastenings if desired using pockets of larger sizes to sort out nails of other and greater lengths.

The apparatus disclosed, which is my preferred embodiment of the invention, comprises a rotary drum the interior of which is provided with a very large number (hundreds or even thousands) of shallow, circular pockets. As the drum rotates such of the nails as are completely within a pocket are carried upwardly, back of a retaining plate, and finally, when they pass beyond the retaining plate toward the top of the drum, are dropped into a trough extending through the drum lengthwise. The lower end of the retaining plate is preferably supplemented by a rotary brush which removes from the pockets such of the over long nails as are partly received within a pocket, these nails then sliding or falling back into the mass of nails in the drum.

With the above and other objects and features in view the invention will now be described with reference to the accompanying drawings and pointed out in the claims.

In the drawings,

Fig. 1 is a side elevation of a portion of a drum for machine sorting of nails;

Fig. 2 is a diagrammatic cross-section of the drum of Fig. 1; and

Fig. 3 is a detail view, also in cross-section, of part of the drum of Fig. 1.

The illustrated apparatus comprises a drum 20 rotated in any suitable manner and provided with a large number of shallow circular pockets 22. As illustrated, this drum is made up of a sheet metal cylinder 24 (Fig. 3) suitably reinforced and having secured to its inner surface a cylindrical perforated member 26 the sheet metal 24 forming the bottoms of pockets whose side walls are formed by the perforations in the cylinder 26. A mass of nails is placed in the drum. As the drum rotates such of the nails as are short enough enter the pockets and are carried upwardly as indicated at 28 in Fig. 3. Any of the nails of greater than the desired length which attempts to enter the pockets

necessarily projects, as shown for example at 30. A retaining plate 32 formed as an arc of a cylinder contacts with the interior of the drum and prevents the escape of such of the 5 nails as are completely within the pockets until they have been carried up pretty well toward the top of the drum. As the pockets pass beyond the top of the retaining plate 32 such of the nails as have been carried up are 10 dropped into a trough 34 extending lengthwise through the drum. The lower edge 36 of the retaining plate 32 is preferably beveled and serves to remove from the pockets such of the nails as project, this action preferably being supplemented by a rotary brush 38 (Fig. 2). After the nails have been 15 treated by the drum until no more (or no substantial number) are carried up and deposited into the trough 34, the nails are removed and 20 treated in a drum having pockets enough larger to sort out the next desired length of nails, or, if desired, the drum may be inclined at such an angle that the sorting will be complete by the time the nails introduced 25 at the upper end have passed through to the lower end of the drum in which case the drum may be advantageously provided with a series of openings 40 at its lower end through which such of the nails as have not been carried up 30 and deposited in the trough 34 may pass. The difference in the diameters of the pockets of two successively used drums should be no more than the tolerated variation of the 35 length of the nails of a given grade. Thus, if a variation of $\frac{1}{16}$ of an inch is all that is permissible, after sorting, for example, in a drum having pockets which will receive nails $\frac{1}{8}$ of an inch long and will reject those of any greater length, they will next be sorted 40 in a drum having pockets which will receive nails up to $\frac{11}{16}$ of an inch long but of no greater length.

Having described my invention, what I claim is new and desire to secure by Letters 45 Patent of the United States is:

1. A machine for sorting metallic fastenings having, in combination, a rotary drum provided with a plurality of shallow, circular pockets of a diameter to receive only those fastenings that are not longer than the desired 50 length, means for removing from the vicinity of the pockets, as the pockets move up during the rotation of the drum, all fastenings other than those completely within a pocket, a retaining plate to prevent the escape of such of the fastenings as are completely received within the pockets as they continue to move up during the rotation of the drum, and a receptacle arranged to receive the fastenings 55 as they pass beyond the retaining plate.

2. A machine for sorting metallic fastenings having, in combination, a rotary drum provided with a plurality of shallow, circular pockets of a diameter to receive only 60 those fastenings that are not longer than the

desired length, a brush to remove from the vicinity of the pockets, as the pockets move up during the rotation of the drum, all fastenings other than those completely within a pocket, a retaining plate to hold such of the fastenings as are completely received within the pockets as they continue to move up during the rotation of the drum, and a trough 70 within the drum positioned to receive the fastenings as they pass beyond the retaining plate. 75

3. A machine for sorting metallic fastenings having a rotary drum arranged to receive fastenings in bulk and provided with a plurality of shallow fastening-receiving 80 pockets of dimensions to receive only fastenings that are not longer than a predetermined length, a brush to remove from the vicinity of the pockets all fastenings that are not wholly within a pocket, and a retaining plate arranged to retain in the pockets such of the fastenings as are completely within a pocket and are therefore not removed by the brush. 85

4. A machine for sorting metallic fastenings having a rotary drum arranged to receive fastenings in bulk and provided with a plurality of shallow fastening-receiving 90 pockets of dimensions to receive only fastenings that are not longer than a predetermined length, a brush to remove from the vicinity of the pockets all fastenings that are not wholly within a pocket, a retaining plate arranged to retain in the pockets such of the fastenings as are completely within a pocket 95 and are therefore not removed by the brush, and a receptacle positioned to receive the fastenings from the pockets as the rotation of the drum carries them beyond the retaining plate. 100

In testimony whereof I have signed my 105 name to this specification.
